DESIGN FOR A SHOWER SPRAY NOZZLE

Walter J. Frost, Kenosha, Wis., assignor to Frost Company, Kenosha, Wis., a corporation of Wisconsin

Application October 13, 1944, Serial No. 115,754

Term of patent 14 years

(Cl. D91—1)

To all whom it may concern:

Be it known that I, Walter J. Frost, a citizen of the United States, residing at Kenosha, in the county of Kenosha and State of Wisconsin, have invented a new, original, and ornamental Design for a Shower Spray Nozzle, of which the following is a specification, reference being had to the accompanying drawing, forming part thereof.

Fig. 1 is a side elevational view of a shower spray nozzle, showing my new design.

Fig. 2 is an end elevational view of same.

I claim:

The ornamental design for a shower spray
nozzle, as shown.

WALTER J. FROST.
